CLAIM

The ornamental design for a gaming machine upper cabinet as shown and described.

DESCRIPTION

FIG. 1 is a right perspective view of a gaming machine upper cabinet showing the new design.

FIG. 2 is an additional right perspective view of the gaming machine upper cabinet shown in FIG. 1.

FIG. 3 is a front view of the gaming machine upper cabinet shown in FIG. 1.

FIG. 4 is a rear view of the gaming machine upper cabinet shown in FIG. 1.

FIG. 5 is a right side view of the gaming machine upper cabinet shown in FIG. 1.

FIG. 6 is a left side view of the gaming machine upper cabinet shown in FIG. 1.

FIG. 7 is a top view of the gaming machine upper cabinet shown in FIG. 1.

FIG. 8 is a right perspective view of a second embodiment of a gaming machine upper cabinet showing the new design.

FIG. 9 is an additional right perspective view of the gaming machine upper cabinet shown in FIG. 8.

FIG. 10 is a front view of the gaming machine upper cabinet shown in FIG. 8.

FIG. 11 is a rear view of the gaming machine upper cabinet shown in FIG. 8.

FIG. 12 is a right side view of the gaming machine upper cabinet shown in FIG. 8.

FIG. 13 is a left side view of the gaming machine upper cabinet shown in FIG. 8; and,

FIG. 14 is a top view of the gaming machine upper cabinet shown in FIG. 8.

The broken lines are directed to environment and form no part of the claimed design.
